ABSTRACT OF THE DISCLOSURE

The disclosure relates to a burner assembly which may be used as a thermal probe and a pilot burner with a 100% fuel shut-off. A housing supports a switch and a pilot valve and a temperature responsive actuator is provided for both the switch and the pilot valve. The housing also supports a tubular burner with the pilot valve supplying gaseous fuel thereto. An ignition coil is energized to heat the temperature responsive actuator and cause the pilot valve to be opened. This permits gas to escape and a pilot flame is ignited by the ignition coil. The pilot flame thereupon continues the heating of the temperature responsive actuator to maintain the pilot valve actuated and also to actuate the switch which de-energizes the ignition coil and at the same time electrically energizes the actuation of a main burner valve to cause gas from a main burner to be ignited by the pilot flame. Upon accidental flame failure, the pilot valve is rapidly closed by the temperature responsive actuator and also the switch is moved to the opposite condition to close the main burner valve for a 100% fuel shut-off.

Cross reference to related cases

The present invention is an improvement on the Thermal Probe and Pilot Burner, Patent No. 3,311,157, issued Mar. 28, 1967 to Charles S. Mertler et al. and assigned to the same assignee as the present invention.

Background of the invention

In gas burners such as used in household appliances, ranges, water heaters and the like, it is a common requirement that these devices be safe in operation. One requirement is that if the main burner be somehow accidentally extinguished, then the flow of gas to such main burner should be cut off. Usually a standing pilot is employed in conjunction with such main burner and current safety regulations permit gas to escape from such pilot burner, even if accidentally extinguished, because this is a small amount of gas, so long as the appliance is adequately vented. However, other gas appliances which may or may not be adequately vented have more strict safety regulations whereby 100% gas shut-off is required in the event that the main burner and pilot burner are extinguished. This means that the small amount of gas escaping from the pilot burner must also be shut off. This is termed a 100% gas shut-off type of control. Such control systems, which in the past have achieved 100% gas shut off, have in general been fairly complicated requiring additional control systems, not only the one for the main burner but an additional control for the pilot burner, and the additional cost and complexity have mitigated against the general commercial use of such 100% gas shut off pilot burners.

Also many of the prior art pilot burners would not provide a combination of both electrical control for an ignition coil or control of an electrical operator for a main burner valve, plus the ability to actuate a pilot valve automatically in response to the presence or absence of the flame for 100% gas shut off.

2

Accordingly, an object of the invention is to provide a burner assembly which obviates the above-mentioned disadvantages.

Another object of the invention is to provide a thermal probe and pilot burner wherein the thermal probe is a temperature responsive actuator to control both a switch and a pilot valve.

Another object of the invention is to provide a pilot burner assembly which is small and compact, simple and trouble-free, and simple to manufacture and operate.

Another object of the invention is to provide a pilot burner assembly having a temperature responsive actuator with first and second leg means, each with different thermal coefficients of expansion.

Another object of the invention is to provide a pilot burner assembly wherein the temperature responsive actuator is tubular with one member inside another to protect the inner member of the temperature responsive actuator.

Summary of the invention

The invention may be incorporated in a burner assembly comprising, in combination, a housing, a tubular burner attached to said housing and extending away from said housing, a valve mounted relative to said housing and connected to supply fluid fuel to said pilot burner, a switch mounted relative to said housing, said burner presenting port means spaced from said housing, temperature responsive actuator means for said switch and said valve, said temperature responsive actuator means including first and second leg means, said first and second leg means each having first and second ends, said first and second leg means having different thermal coefficients of expansion, means mounting said first ends of said first leg means relative to said housing, means interconnecting said second ends of said leg means, said valve having a valve seat and a cooperating valve member, means connecting said second leg means to actuate said valve member, and means connecting said second end of said second leg means to actuate said switch.

Other objects and a fuller understanding of the invention may be had by referring to the following description and claims, taken in conjunction with the accompanying drawings, in which:

Brief description of the drawings

FIGURE 1 is a longitudinal sectional view of the presently-preferred embodiment of the burner assembly according to the present invention;

FIGURE 2 is a top plan view of the assembly of FIGURE 1;

FIGURE 3 is a left-end elevational view of the assembly;

FIGURE 4 is an enlarged longitudinal sectional view of the pilot valve;

FIGURE 5 is an enlarged fragmentary longitudinal sectional view showing the switch mechanism;

FIGURE 6 is an enlarged fragmentary perspective view of the switch in the present assembly;

FIGURE 7 is a right-end elevational view of the assembly to a reduced scale; and

FIGURE 8 is a simplified schematic diagram of a burner ignition circuit in which the present pilot burner assembly is embodied.

Description of the preferred embodiment

The figures of the drawing show the preferred embodiment of the invention, however, numerous changes may be made as will appear hereinafter. The figures of the drawing show a pilot assembly 11 which includes generally a housing 12, a tubular burner 13, a pilot valve 14, a switch 15 and a temperature responsive actuator

means 16. The housing 12 includes a metal plate 18 which is a mounting plate on which the other parts are mounted. Also the housing 12 includes an insulator housing 19 for the switch 15. This insulator housing 19 may be of ceramic material to withstand the high temperatures to which the pilot assembly may be subjected. The temperature responsive actuator means 16 is provided to actuate the pilot valve 14 and switch 15. The pilot valve 14 is connected to supply gaseous fuel to the tubular pilot burner 13. The temperature responsive actuator means 16 includes first and second leg means 21 and 22, respectively, and each of the first and second leg means has first and second ends. The tubular pilot burner 13 is one part of the first leg means 21 and has a first end 23 fixedly mounted on the housing plate 18. The second end 24 of the pilot burner 13 is fixedly attached to an end plate 25, as by welding.

A valve rod 27 is disposed inside said tubular pilot burner 13 as part of said second leg means 22. The valve rod 27 has a first end 28 which is a conical valve member to cooperate with a valve seat 29 inside said tubular burner 13 at the first end 23 thereof. The valve rod 27 has a second end 30 which is externally threaded to be threaded into internal threads in the second end of the pilot burner 13. A screwdriver slot permits adjustment of this valve rod 27 to adjust the position of the valve member 28 relative to the valve seat 29. The valve rod 27 is of considerably smaller diameter than the inside diameter of the tubular burner 13 to permit gas passage beyond the valve seat 29. Gas flow may then emit from ignition ports 31 and flame ports 32 on this tubular burner 13. This will establish a pilot flame 33.

The temperature responsive actuator means 16 also includes a switch actuator tube 36 as part of said first leg means 21 and a switch actuator rod 37 loosely disposed inside said tube 36 as a part of said second leg means 22. The switch actuator tube 36 has a first end 38 carried in the housing plate 18, as better shown in FIGURE 5. The switch actuator tube 36 has a second end 39 fixedly carried in the end plate 25. The interior of this second end 39 is threaded to receive an adjusting screw 40. The second end of the switch actuator rod 37 abuts this adjusting screw 40 and the first end of the switch actuator rod 37 is slidably disposed in the switch housing 19 to actuate the switch 15.

The first and second leg means 21 and 22 have different thermal coefficients of expansion. In this preferred embodiment the first leg means 21 has a high positive thermal coefficient of expansion, and the second leg means 22 has a low positive coefficient of expansion. The first leg means 21 includes the tubular pilot burner 13 and the switch actuator tube 36, both of which may be made from high expansion stainless steel. The second leg means 22 includes the valve rod 27 and the switch actuator rod 37. The valve rod 27 may be made from ordinary stainless steel which has a low positive thermal coefficient of expansion, and the switch actuator rod may be made from a ceramic material which has a low positive thermal coefficient of expansion, and also serves to insulate the switch mechanism from the metal plate 18, which would be ground.

The switch 15 is mounted inside the insulated housing 19 on the metal plate 18. This switch 15 has a movable blade 43 carrying movable contacts on each side of the free end thereof. The movable blade 43 is mounted by a rivet 44 to a terminal 45. The movable blade 43 is normally biased to push against the switch actuator rod 37, but in the cold or room temperature position of the pilot assembly 11, the movable blade 43 is urged to the left as viewed in FIGURES 1 and 5 so that the movable blade 43 is in contact with a fixed contact 46 which is mounted by a rivet 47 to support arm 48. This support arm 48 carries one end of an ignition coil 49 which extends in fuel-igniting relationship to the ignition ports 31 of the tubular burner 13. The other end of this igni-

tion coil 49 is electrically connected to and supported on a support arm 50 which is connected to a terminal 51.

The switch actuator rod 37 engages a projection 52 on the movable blade 43. When permitted by the expansion of the tubular burner 13, the inherent bias of the movable blade 43 will move the switch actuator rod 37 to the right as viewed in FIGURES 1 and 5, that is, toward the end plate 25 and this will permit the movable contacts of the movable blade 43 to engage a second fixed contact 54. The fixed contact 54 is mounted by a rivet 55 to a terminal 56. A protective metal shield 58 is fastened at only one end near the second end of the tubular burner 13, as by welding, and abuts the bottom of the housing plate 18, to provide physical protection for the ignition coil 49. An insulator 59 is carried by this metal shield 58 to give physical support to and electrically insulate this ignition coil 49.

The FIGURE 8 shows one typical application of many in which this pilot assembly 11 may be used. This FIGURE 8 is a schematic diagram of an oven burner circuit showing only a broil burner 61, however, the burner 61 shown may be a bake burner or there may be both broil and bake burners in a double-burner oven. The movable blade 43 is connected through terminal 45, a conductor 62, a manual switch 63, to a lower end of a secondary winding 64 of a step-down transformer 65, the primary winding 66 thereof being connected through a switch 67 across a conventional 115 volt power source 68. In one practical embodiment, the secondary voltage 30 of the transformer 65 may be 12 volts.

The upper end of the transformer secondary winding 64 is connected through a clock switch 69, an oven thermostat switch 70, and a conductor 71 to the terminal 51. The oven thermostat switch 70 is also connected through a conductor 72 to an operating coil 73 of an electrical operating device to actuate a main gas valve 74. The other end of the operating coil 73 is connected by a conductor 75 to the terminal 56. The main gas valve 74 is connected in the gas supply line to the main burner 61. A manually operable main shut-off valve 76 is connected between a gas inlet manifold 77 and the electrically operated main burner valve 74.

The switch 63 is under the control of a manually operable control knob 78. The control knob 78 is also arranged to operate the switch 67 and to operate a pilot burner valve 79 connected to control the flow of gas from the inlet side of the main shut-off valve 74 to the pilot assembly 11.

Operation

The pilot assembly 11 may be used with a gaseous fuel to control the pilot flame 33 by controlling the pilot valve 14 as a part of the pilot assembly. Also, the switch 15 is controlled by the temperature responsive actuator means 16 to control energization of the ignition coil 49 which ignites the pilot flame 33 and also controls energization of the operating coil 73 which controls the main gas valve 74 to control gas flow to the main burner 61. When gas is emitted from the main burner 61 it will be ignited by the pilot flame 33. Upon extinguishment of the flame, the temperature responsive actuator means 16 controls the pilot valve 14 to close same and also controls the switch 15 to de-energize the operating coil 73 and hence close the main gas valve 74.

FIGURES 1 and 5 show the pilot assembly 11 in the normal or room temperature position, in which case the movable blade 43 is in engagement with the first fixed contact 46. When it is desired to light the main burner 61, the manual control knob 78 is moved to permit gas flow through the pilot burner valve 79 to the pilot assembly 11. At the same time, movement of the control knob 78 energizes the transformer 65 through the switch 67 and also the manual switch 63 is closed to permit energization from the secondary 64 to the ignition coil 49. The energization circuit of the ignition coil 49 is 75 from the bottom of the secondary winding 64, through

manual switch 63, conductor 62, terminal 45, movable blade 43, fixed contact 46, support arm 48, ignition coil 49, support arm 50, terminal 51, conductor 71, oven thermostat switch 70, clock switch 69, and return to the upper end of the secondary 64. The ignition coil 49 is thereupon heated to impart heat to the temperature responsive actuator means 16. The tubular pilot burner 13 is a part of the first leg means of this temperature responsive actuator 16 and accordingly since it has a high co-efficient of expansion this pilot burner 13 will expand away from the housing 12. The inner valve rod 27 has a low coefficient of expansion and accordingly it will also move to the right to open the pilot valve 14. Gas will thereupon flow through the pilot conduit 80 into the tubular pilot burner 13 and out through the ignition ports 31 and flame ports 32. Gas emitting from the ignition ports 31 will be ignited by the ignition coil 49 and this will establish the pilot flame 33, primarily from the flame ports 32.

The heat from the pilot flame 33 will envelope both the tubular pilot burner 13 and the switch actuator tube 36 to heat both of these tubes. This pilot flame 33 will therefore maintain the tubular pilot burner 13 heated and elongated to maintain the pilot valve 14 in the open condition. The heat from the pilot flame 33 will also heat the switch actuator 36 tube which is a part of the first leg means 21 of the temperature responsive actuator 16. Because of the high thermal coefficient of the switch actuator tube 36, it will expand to the right, as viewed in FIGURE 1, and the inherent bias of the movable blade 43 will move the switch actuator rod 37 to the right, permitting the movable blade 43 to move away from the fixed contact 46 into engagement with the fixed contact 54. This will de-energize the ignition coil 49, which is no longer needed because the pilot flame 33 is already established. Engagement of the movable blade 43 with the fixed contact 54 will now energize the operating coil 73 of the main gas valve 74. This energization circuit is from the lower end of the secondary 64, through the manual switch 63, conductor 62, terminal 45, movable blade 43, fixed contact 54, terminal 56, conductor 75, operating coil 73, oven thermostat switch 70, clock switch 69, and return to the secondary winding 64. Energization of this operating coil 73 will open the main gas valve 74 and the gas emitting from the main burner 61 will be ignited by the pilot flame 33.

The main burner 61 may be turned off simply by turning the manual control knob 78 to the off position which will de-energize the electrical circuit and hence de-energize the operating coil 73. This shuts off the main gas valve 74. Pilot gas will continue to be emitted from the tubular pilot burner 13 until it cools sufficiently that the pilot burner 13 contracts and closes the pilot valve 14. This will take only a matter of seconds in a typical application.

Upon accidental flame failure, as by a sudden gust of wind, which extinguishes both the main burner and the pilot flame, the temperature responsive actuator 16 will cool to gradually close the pilot valve 14. At the same time the switch actuator tube 36 will gradually cool and contract to move the movable blade 43 away from fixed contact 54. This will de-energize the operating coil 73 and accordingly stop gas emission from the main burner 61. When the movable blade 43 of the switch 15 engages the fixed contact 46, the ignition coil 49 will again be energized to heat the temperature responsive actuator means 16. This will again set in motion the cycle of events set forth above to rekindle the pilot flame and later the main burner 61.

The end plate 25 inter-engaging the second ends of the tubular pilot 13 and the switch actuator tube 36 will help establish that both the tubular burner 13 and tube 36 expand together with heat. Both of these tubes may be made from the same material so that they will inherently expand together with the same temperature rise. The fact that the first leg means 21, including pilot burner 13

and switch actuator tube 36, surround and encase the second leg means 22, including valve rod 27 and switch actuator rod 37, gives protection to these inner rods to make the device compact and yet rugged. The fact that the first and second leg means 21 and 22 include a rod within a tube means that both parts of the temperature responsive actuator 16 are established at approximately the same temperature when operating at a stable operating condition in the pilot flame 33.

The pilot assembly 11 may be used with two burners 61, for example, one pilot assembly for each burner. In such case the main gas valve 74 may be a three-way valve with another outlet to a second main burner. Also in such case the pilot burner valve 79 could be a three-way valve and the manual switch 63 a three-way switch. Turning the manual control knob 78 in the appropriate direction would cause either the main burner 61 or the second main burner to be ignited. Because the pilot assembly 11 achieves a 100% gas shutoff, namely, a shutoff of not only the main gas flow from burner 61 but also the gas flow from the tubular burner 13, it is possible to eliminate the pilot burner valve 79 where only a single pilot assembly 11 is being used, however it is shown here for completeness.

The first and second leg means 21 and 22 are interconnected by the threads at the second end of the valve rod 27. This assures that the combination of movements of the first and second leg means will actuate the pilot valve 14. Also the first and second leg means 21 and 22 are interconnected for actuation by the threads at the adjusting screw 40 and the second end of the switch actuator tube 36. The switch actuator rod 37 abuts this adjusting screw 40 and also abuts the movable blade 43 at the projection 52 in order to cause actuation of this switch 15 by the combination of movements of the first and second leg means 21 and 22.

Although this invention has been described in its preferred form with a certain degree of particularity, it is understood that the present disclosure of the preferred form has been made only by way of example and that numerous changes in the details of the circuit and the combination and arrangement of circuit elements may be resorted to without departing from the spirit and scope of the invention as hereinafter claimed.

What is claimed is:

1. A burner assembly comprising, in combination, a housing,
a tubular burner attached to said housing and extending away from said housing,
a valve attached to said housing and connected to supply fluid fuel to said burner,
a switch attached to said housing,
said burner presenting port means spaced from said housing,
temperature responsive actuator means for said switch and said valve,
said burner port means being directed toward said temperature responsive actuator means,
said temperature responsive actuator means including first and second leg means,
said first and second leg means each having first and second ends,
said first and second leg means having different thermal coefficients of expansion,
means mounting said first end of said first leg means on said housing,
means interconnecting said second ends of said leg means,
said valve having a valve seat and a cooperating valve member,
means connecting said second leg means to actuate said valve member,
means connecting said second end of said second leg means to actuate said switch,
and heating of said tubular burner effecting opening of said valve to permit emission of fluid fuel to be

- ignited and the flame thereof further heating said temperature responsive actuator means.
2. A burner assembly as set forth in claim 1 wherein said first leg means has a high positive temperature coefficient of expansion and said second leg means has a low positive temperature coefficient of expansion.
3. A burner assembly as set forth in claim 1, wherein said valve seat is near said housing, and means to actuate said valve member from said first end of said second leg means.
4. A burner assembly as set forth in claim 1 wherein said valve seat is closely adjacent said first end of said tubular burner, an inner rod inside said tubular burner as part of said second leg means, and said cooperating valve member is coaxially connected on said first end of said inner rod.
5. A burner assembly as set forth in claim 1 wherein said first leg means includes said tubular burner and a switch actuator tube, said second leg means includes a valve rod as an inner rod inside said tubular burner and includes a switch actuator rod inside said switch actuator tube, and an end plate interconnecting said second ends of said tubular burner and said switch actuator tube.
6. A burner assembly as set forth in claim 5 wherein said tubular burner and said switch actuator tube have a high positive temperature coefficient of expansion, said valve rod is metallic and has a low positive temperature coefficient of expansion, and said switch actuator rod is ceramic and has a low positive temperature coefficient of expansion.
7. A burner assembly as set forth in claim 5 including threaded means interconnecting the second ends of said valve rod and said tubular burner, a threaded adjusting screw at said second end of said switch actuator tube, and the second end of said switch actuator rod bearing against said adjusting screw.
8. A burner assembly as set forth in claim 1 including an inner rod inside said tubular burner as part of said second leg means, and wherein said tubular burner expands upon being heated to move said inner rod and move said valve member away from said valve seat to permit emission of fluid fuel which will ignite and the flame therefrom will maintain said tubular burner heated and expanded to maintain said valve open.
9. A burner assembly as set forth in claim 1 wherein said burner flame heats said first leg means to act through said second leg means for actuation of said switch to an alternate switch condition, a main gas valve, and means controlled by actuation of said switch to energize said main gas valve.
10. A burner assembly as set forth in claim 1 including an ignition coil extending in igniting relation to the port means of said tubular burner, and means controlling energization of said ignition coil through said switch.
11. A burner assembly as set forth in claim 1 wherein said switch actuator means includes a switch actuator tube as part of said first leg means and includes a switch actuator rod as part of said second leg means, said second ends of said switch actuator rod and tube being interconnected, and said first end of said switch actuator rod being slidably disposed inside said first end of said switch actuator tube and disposed to actuate said switch.
12. A burner assembly as set forth in claim 1 wherein said first leg means is tubular and said second leg means is disposed inside said tubular first leg means.
13. A burner assembly as set forth in claim 1 wherein said first and second leg means are established at sub-

stantially the same temperature under stable conditions of operation in the flame from said port means of said tubular burner.

14. A burner assembly as set forth in claim 1 wherein said first leg means includes said tubular burner and a switch actuator tube, said second leg means includes an inner rod inside each of said tubular burner and said switch actuator tube, said tubular burner and said valve rod having different thermal coefficients of expansion to actuate said valve between open and closed positions upon the presence and absence of a burner flame, and said switch actuator tube and rod having different thermal coefficients of expansion to actuate said switch between first and second conditions upon the presence and absence of a burner flame.
15. A burner assembly as set forth in claim 14 wherein said tubular burner and switch actuator tube having high positive temperature coefficients of expansion and said valve rod and switch actuator rod have low positive coefficients of expansion.
16. A burner assembly as set forth in claim 1 including an ignition coil extending in igniting relation to the tubular burner, said switch actuator means including a switch actuator tube and a switch actuator rod slidably disposed therein and each having first and second ends, said tubular burner and said switch actuator tube constituting said first leg means, an inner valve rod inside said tubular burner, said valve rod and said switch actuator rod constituting said second leg means, an end plate fixedly attached to the second ends of said tubular burner and said switch actuator tube, threaded means interconnecting said second ends of said valve rod and said tubular burner, an adjusting screw threadably inserted in said second end of said switch actuator tube, said switch actuator rod acting between said adjusting screw and said switch, said tubular burner and said switch actuator tube having a high positive temperature coefficient of expansion, said valve rod having a low positive temperature coefficient of expansion, said switch actuator rod being ceramic with a low positive temperature coefficient of expansion, a main burner valve, means connecting said switch to establish actuation of said main burner valve, and circuit means interconnecting said ignition coil and said switch whereby heating of said tubular burner by energization of said ignition coil through said switch causes elongation of said tubular burner to open said first mentioned valve and the emission of gaseous fuel therefrom is ignited by the ignition coil and the burner flame therefrom maintains said tubular burner elongated, and whereby the burner flame heats the switch actuator tube to expand same and actuate said switch to de-energize said coil and actuate said main burner valve.
